TRAILER HITCH BAR

Roger C. Silver and Frank A. De Puydt, Des Moines,
Iowa, assignors to Dico Corporation, Des Moines, Iowa,
a corporation of Iowa

Filed July 19, 1962, Ser. No. 70,982

Term of patent 14 years

(CL D14—6)

FIG. 1 is an elevational view looking toward one side of a trailer hitch bar showing our new design;

FIG. 2 is an elevational view looking toward the opposite side thereof;

FIG. 3 is a top plan view of the unit;

FIG. 4 is a bottom plan view of the unit;

FIG. 5 is a front elevational view of the unit; and

FIG. 6 is a rear elevational view thereof.

We claim:

The ornamental design for a trailer hitch bar, substantially as shown.
